UNITED STATES PATENT OFFICE.

NICHOLAS ZOGG, OF NEW YORK, N. Y.

SASH-WEIGHT ATTACHER.

SPECIFICATION forming part of Letters Patent No. 429,403, dated June 3, 1890.

Application filed February 27, 1889. Serial No. 301,324. (No model.)

To all whom it may concern:

Be it known that I, NICHOLAS ZOGG, a citizen of the United States, and a resident of the city of New York, in the county and 5 State of New York, have invented a new and useful Improvement in Sash-Weight Attachers, of which the following is a specification.

The object of my invention is to furnish a very simple, secure, and readily-applied device for attaching window-sash-balancing weights to their respective sash-chains; and it consists of a wire forming a loop for the reception of the perforated end of the sash-weight, one shank of the wire loop having an 15 angular bend forming a lateral projection, which is curved slightly and notched or grooved transversely upon its upper surface, and is inserted through the end link of the chain, and the other shank of the wire loop 20 having a loop or eye large enough to be passed upon the said lateral projection, so as to surround the same and lodge in the said notch or groove, as will be hereinafter fully described, and specifically claimed.

25 In the accompanying drawings, Figure 1 represents an edge view of my said improved device attached to a sash weight and chain. Fig. 2 is a side view of the same as seen in direction of arrow 1, Fig. 1. Fig. 3 is an edge 30 view from the same edge as in Fig. 1, showing the device in its normal condition, as when detached. Fig. 4 is a side view of Fig. 3, seen in direction of arrow 2.

A designates the sash-chain; B, the sash-weight, and C my improved attacher. The latter is a wire bent to form a sufficiently-large loop to comfortably receive the weight, to which it is attached by passing one of the loop-shanks *a* or *c* through the hole or eye *b* 40 of the weight. For the purpose of interlocking the shanks *a* *c* and attaching to the chain, one of the shanks, as *a*, has at its end an elbow or angular bend, thus forming a lateral projection *e*. This is slightly curved downward, as shown in Figs. 2 and 4, and upon its upper surface is made transversely a notch or groove *n*. The other shank *c* has upon its end an eye or loop *d*, adapted to be passed upon, so as to surround the lateral projection *e* of the other shank. The weight having been first suspended in a loop, as in Figs. 1 and 2, the projection *e* is inserted through

the last link of the chain A, after which the loop or eye *d* of the shank *c* is passed over the end of the projection *e*, upon the upper 55 surface of which the loop is adjusted to press tightly, so as to be necessarily sprung over the curved end before it reaches the notch or groove *n*, into which it then lodges, the wire 60 loop being then in position, as in Fig. 2, suspended upon the arm of the projection *e* in the end link of the chain, the two shanks *a* *c* being thus interlocked and occupying the position shown—viz., one at each side of the link. The notch *e*, though, preferably may 65 be dispensed with. In making the wire loop C the wire is bent so that in its normal shape, when the eye *d* is disengaged from the arm *a*, the shank *c* occupies relative to the other shank *a* the position in Fig. 3—i. e., the ends 70 spring apart—so as to always leave an opening ready for introducing one of the shanks through the hole *b* in the weight, yet in such position relative to the notch *n* that the face of the eye *d* is normally in the same plane as 75 the said notch, (see Fig. 4,) so that the shank *c* must be sprung out beyond the end of the arm *e*, as well as laterally relative to the same movement, before it can be entered upon the said arm. By giving to the wire loop the afore- 80 said normal shape it has no tendency, when once passed upon the arm *e*, to be displaced or slip off from the said arm, whether or not it be retained by a notch, as *n*.

Having thus described my invention, I 85 claim as new and desire to secure by Letters Patent—

1. The combination, with the sash cord and weight, of the wire weight and chain connecting loop, one of whose members has the 90 lateral slightly hook-pointed terminal arm inserted through the chain and having a notch in the back or upper side of the part projecting beyond the chain-link, and the other member has an eye in the upper end 95 engaging the notch of said terminal arm by springing into it on the opposite side of the chain-link to the first-mentioned member, so that both members support said terminal arm engaging the link, substantially as described. 100

2. The combination, with the sash cord and weight, of the wire weight and chain connecting loop, one of whose members has the lateral slightly hook-pointed terminal arm

inserted through the chain and having a notch in the back or upper side of the part projecting beyond the chain-link, and the other member has an eye in the upper end 5 engaging the notch of said terminal arm by springing into it on the opposite side of the chain-link to the first-mentioned member, so that both members support said terminal arm engaging the link, and the members of the 10 loop having the set laterally diverging from the plane of the bend of the loop, whereby in the disconnected condition the ends are normally open for inserting the said lateral pro-

jection of the one member through the end link of the sash-chain unobstructed by the eye of the other member, substantially as described.

In testimony that I claim the foregoing as my invention I have signed my name, in presence of two witnesses, this 23d day of February, 1889.

NICHOLAS ZOGG.
